UNITED STATES PATENT OFFICE.

JEAN ROMEYN, OF BRUSSELS, BELGIUM.

STARTING VALVE-GEAR FOR INTERNAL-COMBUSTION MOTORS.

1,073,633.

Specification of Letters Patent. Patented Sept. 23, 1913.

Application filed June 17, 1912. Serial No. 704,219.

To all whom it may concern:

Be it known that I, JEAN ROMEYN, 66 Avenue Jean Volders, Brussels, Belgium, have invented certain new and useful Improvements in Starting Valve-Gear for Internal-Combustion Motors; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

Certain internal combustion motors have hitherto been fitted with valve gear for the purpose of starting them by means of compressed air before they begin to work on fuel and to effect this, it has been necessary first to operate the starting valve, keeping the fuel valve closed, then, as soon as the motor is started, to throw the starting valve out of action and the fuel valve into action.

The present invention relates to an arrangement by means of which these conditions can be realized and the result is obtained essentially by transmitting the action of the cam operating the valves to the said valves through a member that is variable in its height.

The appended drawings show by way of illustration or example two forms or embodiments of the invention.

Figure 1 is a vertical section taken on the line E, F Fig. 3. Fig. 2 is a vertical section of a modified form of the invention. Fig. 3 is a cross section taken on the line A, B Fig. 1. Fig. 4 is a cross section taken on the line C, D Fig. 2.

The modification shown in Fig. 2 differs only from the arrangement shown in Fig. 1 in the method of controlling the fork 5 hereinafter described. In both cases the cam shaft 1 carries as usual one cam for the starting valve and one cam for the fuel valve for each cylinder. In reversible motors each cam will be replaced by a pair of cams in juxtaposition, one for running ahead and the other for running astern. Movement is transmitted from the cam to the valve rods 13 by means of intermediate members embodied in the gear for working each valve.

To put the valves into or out of action it is necessary to form the aforesaid intermediate members in such a manner that it

is possible to vary their height H, between the cams 2 and the rollers 14 of the valve rods 13.

Each of the intermediate members is constituted as follows:—A fork 5 oscillating around the working shaft 3, is formed or provided with an inclined surface 7 on which the wedge 12 slides. This fork 5 carries a roller 6 which is operated by the cam 2. When the working shaft is caused to turn, the cam 4 keyed thereto pushes the roller 9, the ends of whose spindle form guide blocks working in the guides 18 formed in the forks 5 and the said roller 6 transmits its motion to the wedge 12 by a connecting rod 11. When the wedge 12 is pushed toward the left, the cam 2 actuates the valve rod 13, but as soon as it returns to the bottom of the inclined plane, in consequence of the rotation of the cam 4, all connection between the cam 2 and the valve ceases. In the embodiment of the invention shown in Figs. 1 and 3, the fork is then raised by the spring 8 and the cam 2 turns freely under the roller 6.

In the embodiment shown in Figs. 2 and 4, the spring 8 is replaced by a lever 15 pivoted to the shaft 16. When the wedge 12 has returned to the bottom of the inclined plane 7, the said lever 15, actuated by the cam 17, raises the fork 5 sufficiently to prevent the roller 6 from engaging with the cam 2 as it rotates. When the motor is stopped, the working shaft is in such a position that all the forks are raised.

In both of the embodiments just described the working shaft may be manually controlled by means of a lever which is connected therewith and actuated by a toothed sector: according to the different positions given to this lever, the positions of the cam 4 and the fork 5 are regulated, and consequently the valve rod 13.

It should be observed that in multi-cylinder motors the distribution shaft 1 and the working shaft 3 run the whole length of the motor. On reversible motors the shaft 3 can make, in addition to its movement of rotation, a longitudinal sliding movement which renders it possible when the motor is stopped, that is, when all the forks are raised, to bring the rollers 6 either to engage the go-ahead cams or the go-astern cams. Thus, by causing the working shaft to turn, the motor can be started in either direction as desired.

By giving the cams 4 a suitable profile and a proper position and direction it will be possible to start by air, say a four-cylinder motor, with the cranks in any position whatever and thereafter to pass gradually to running on fuel in such a way that there will always be available a turning couple sufficient to prevent the stoppage of the motor, even where the fly-wheel is very light.

10 Claims—

1. In starting valve gear for internal combustion motors, the combination of a fork oscillating on a working shaft, an inclined plane carried by said fork, a wedge sliding on said plane, a cam keyed on the working shaft and effecting the movement of said wedge.
- 15

2. In a starting valve gear for internal combustion motors, the combination of a fork oscillating on a working shaft, an inclined plane carried by said fork, a wedge which slides on said plane, a cam keyed on the working shaft and effecting the movement of said wedge, a lever acting upon said oscillating fork, a cam keyed on the working shaft and effecting the movement of said lever.
